UNITED STATES PATENT OFFICE

154,827

DESIGN FOR A TEXTILE FABRIC OR SIMILAR ARTICLE

William O. Wells, Jr., Kenilworth, Ill., assignor to Wells Lamont Corporation, Chicago, Ill., a corporation of Illinois

Application April 29, 1949, Serial No. 2,332

Term of patent 14 years

(Cl. D92—1)

To all whom it may concern:

Be it known, that I, William O. Wells, Jr., a citizen of the United States, residing at Kenilworth, in the county of Cook, State of Illinois, have invented a new, original, and ornamental Design for a Textile Fabric or Similar Article, of which the following is a specification, reference being had to the accompanying drawing, forming a part thereof.

The figure is a plan view of a textile fabric, showing my new design. The design unit is outlined by broken lines and is repeated vertically on the drawing as indicated by the extensions beyond the unit boundaries.

I claim:

The ornamental design for a textile fabric or similar article, as shown and described.
